(57) **CLAIM**

The ornamental design for a timeline for a computer display,
as shown and described.

DESCRIPTION

FIG. 1 is a front view of a timeline for a computer display
according to the invention;

FIG. 2 is front view of a second embodiment thereof;

FIG. 3 is a front view of a third embodiment thereof; and,

FIG. 4 is a front view of a fourth embodiment thereof.
The broken line drawings of vertical lines in the top horizontal
portion and faces in all views are for illustrative
purposes only and form no part of the claimed design.

1 Claim, 4 Drawing Sheets

FIG. 1

FIG. 2

FIG. 3

FIG. 4
